UNITED STATES PATENT OFFICE

CHARLES J. MORITZ, OF EFFINGHAM, ILLINOIS

ROAD GRADER

Application filed June 20, 1930. Serial No. 462,575.

My invention relates in general to road graders, and more in particular to a road grader adapted to ride on a finished road surface and operate on the road shoulder at the side of the finished road surface.

The principal object of the invention is the production of an improved machine of this character which can be turned in a relatively small space.

10 Another object is the provision of a machine of this character wherein the carriage portion which rides on the road surface is adapted to be controlled easily.

15 Another object is to provide improved means for preventing the shifting of the carriage when unusual strain is applied to the mold board.

20 Other objects and features of the invention will be apparent from a consideration of the following description taken with the accompanying drawings, wherein,

Fig. 1 is a plan view showing the complete machine,

25 Fig. 2 is an enlarged side elevational view thereof with some of the parts broken away to conserve space and bring out more clearly certain features of the carriage,

Fig. 3 is an enlarged sectional view taken 30 along the line 3—3 of Fig. 1,

Fig. 4 is a fragmentary bottom plan view showing the details of the steering mechanism,

Fig. 5 is an enlarged sectional view taken 35 along the line 5—5 of Fig. 1,

Fig. 6 is an end elevational view showing one embodiment of the means for preventing side shifting of the carriage, and,

Fig. 7 is a fragmentary vertical sectional view taken along the line 7—7 of Fig. 2.

40 In its general aspects, the road shoulder machine of my invention includes a wheeled carriage adapted to travel along the finished roadway, the carriage having side extensions for supporting a mold board and adjusting means therefor, and the mold board being adapted for operating on the road shoulder; that is, the level earth extension usually provided at the edge of most hard pavements. The grading machine of my invention has 45 other applications, however.

In my copending application Serial No. 461,860, filed June 18, 1930, I describe certain novel means for controlling the operation of the mold board at the side of the grader frame. In my present invention I am interested primarily in the operation of the wheeled carriage and the features of the present invention are directed more particularly thereto.

Referring now to the drawings, the wheeled carriage includes a plurality of longitudinal members 10 in the form of channel irons, with a plurality of cross pieces 11, and reinforcing bracing 12. The longitudinal frame members 10 have additional members 10' on the outside thereof extending from behind the front wheels to the rearmost portion of the frame, and are so connected thereto and to the cross members as to be an integral part of the frame proper. At an intermediate portion of the frame there is a side extension 13 supporting a bracket 14 which, through suitable means, carries a mold board 16. Means not shown here in detail are provided by adjusting the bracket 14 and other supporting portions of the mold board so that the position of the mold board can be regulated with respect to the grader frame or wheeled carriage which the frame forms a part of. At the front of the frame one of the cross members is extended to form a side projection 17, to the outer end of which a drawbar 18 is connected to more directly pull upon the mold board.

45 The carriage frame is provided with rear wheels 19, rotatably mounted on the projecting ends of a rear axle 21 which is suitably secured to the longitudinal members 10 and 10', and at the front of the frame a transverse member 22 is provided in place of a front axle, and at each end thereof, top and bottom wheel mounting castings 23 and 24 are secured. The front wheels are mounted on shafts 27 having a swivel extension 28 with journaled portions 28a and 28b extending into the top and bottom mountings. As Fig. 3 illustrates, this forms a firm mounting for the front wheels and at the same time permits the axle to be turned for steering purposes.

For the purpose of steering the front wheels I provide a steering column 31 extending through apertures in two plates 32 carried by the frame members and having a collar 33 engaging the bottom one of the two said plates and a casing 34 engaging the top one of said plates, whereby the steering wheel is held firmly but rotatably in position. A pinion 36 is secured to the bottom of the steering column 31 and engages with a rack 37 formed on a member 38. This member 38 is reciprocably mounted on a guide rod 39 secured under the frame by brackets 41 and has a guide extension 38a which rides along the frame member and so prevents the rack carried by member 38 from turning. A rod 42 extends from the rack carrying member to an arm 43 which has a boss 44 pinned to the member 28 so that turning of the column 31 will serve to turn the wheel immediately adjacent the arm 43. In order to transfer the movement to the opposite wheel the usual construction is employed, including an arm 45 secured to turn with the wheel, with a tie rod 46 connected to a similar arm carried by the opposite wheel supporting member.

Since the mold board is supported by the wheeled carriage which travels on the finished road, and at the side thereof, it is obvious that there will be a tendency for the carriage to shift on the road surface, particularly if an unusual load is applied to the mold board. This tendency is greatly overcome by the hitch which I employ in the form of a pair of rods 47 and 48 which may be adjusted greatly to minimize this tendency. Also, the fact that the drawbar 18 is somewhat more directly in line with the draft means, has a tendency to minimize the shifting. I show, however, additional means for securing this result, these means being shown particularly in Figs. 1 and 6.

The frame members extend beyond the rear wheels to support a rod or axle 48 on which a flanged wheel 49 is mounted, this flanged wheel being adapted to be adjusted to engage the edge of the finished road surface 51. I provide means for adjusting this flanged wheel vertically as well as laterally so that the position at which the grader will be drawn along the edge of the road can be controlled, and the possibility of the flanged guide wheel supporting the weight of the machine along the edge of the road with the concomitant tendency to cause a cracking thereof, is done away with.

As to the method of mounting the axle 48 on which the flanged wheel is rotatably mounted, the end of the axle 48 is pivoted at 52 to a bolt 53 threaded in a guide 54 carried by the frame. At the opposite side of the frame the axle is slidably supported in a sleeve 56 to which a bifurcated member 57 is pivotally attached at 58. This bifurcated member 57 is guided between the frame mem-

bers 10 and 10' and has a swivel connection to a bolt 59 threaded in a boss 61 carried by a plate 62. With this arrangement it is obvious that turning of the bolt 59 will tend to raise or lower the bifurcated member 57, carrying with it the axle 48 with its flanged wheel 49. Similarly turning the bolt 53 will cause a transverse movement of the axle 48 so that the position to which the flanged wheel is adjusted beyond the line of draft of the wheels can be regulated.

I wish to call attention to the fact that this means for preventing the side shifting of the carriage is mounted behind the rear wheels, or a considerable distance behind the virtual point of pivot, which would be established if a shifting of the carriage would occur.

Due to the fact that the carriage is relatively long, and the mold board at the side adds greatly to the width thereof, it is sometimes difficult to make a turn, particularly on a narrow road. I provide means for turning the road shoulder machine of my invention, the improved means being shown particularly in Figs. 2, 3, and 5, and consisting of a fifth wheel arrangement so designed as to raise the front wheels clear of the road to permit the carriage to be moved directly about the rear wheels as a pivot. While this feature is shown as raising the front wheels, it is obvious that it can be located in a different position and serve to raise the rear wheels instead, so that the carriage can be turned about the front wheels.

In effecting the desired result I provide a fifth wheel casting member 66 with a vertical opening for receiving a column 67 bifurcated at 68 to receive a wheel 69. The column is slidably supported in the casting 66 and is secured at the top thereof to a bolt 71 threaded in the upper portion of the casting 66. This casting 66 is pivotally connected to the frame at 72 by arms 73 and is prevented from shifting about the pivot by means of a pin 74 which extends through a bracket 76 carried on the cross member 22 and an opening in an extension 66' of the casting 66. The pin 74 slides in a guide 77 and is actuated by a hand piece 78 which also engages against the member 77 and prevents the full withdrawal of the pin or bolt 74. Intermediate the arms 73 a latching member 79 is pivoted, this member normally being held in an upward position, but adapted to engage against the member 72 when the entire fifth wheel supporting mechanism is elevated, so that the fifth wheel may be held in a position to clear any obstacles whatsoever that may be in the road. During normal use of the road shoulder machine the wheel 69 is raised by turning the column 71 by means of the hand wheel 71'. But if the machine is to be transported over great distances, and there may be obstacles to be cleared, the fifth wheel may

be further raised by raising the entire assembly about the pivot 72 and supporting it in this position by placing the latch arm 79 in against the member 22 as shown in dotted lines in Fig. 5.

From the description of the fifth wheel 69 it is apparent that as the hand wheel 71' is turned the fifth wheel 69 will also turn bodily therewith. This construction is used because it is often necessary to turn in such a way that the fifth wheel will have to move out over the road shoulder which, being considerably softer than the hard road, may have a tendency to sink beneath the weight of the machine. With the present arrangement a board or section of timber 81 may then be placed upon the road shoulder or other path over which it is desired to direct fifth wheel, and the fifth wheel may then be steered along the relatively narrow board or timber.

There are certain practical advantages in the use of a machine of this type with mechanism disposed as shown in the drawings. The steering wheel 30 is placed at the edge of the road and immediately in advance of the mold board so that the operator of the carriage, being in direct line with the edge of the road which he is using as a guide, can operate the carriage and keep it adjusted to exactly the right position. In this position he is also able to watch the operation of the flanged wheel by turning his head, and this is also of importance.

It is believed that the operation and method of using my machine will be perfectly clear from the foregoing description. Needless to say, the details may be modified considerably and the invention is not limited by the particular type shown and described.

What I claim is new and desire to protect by Letter Patent of the United States is:

1. In a road shoulder machine, a carriage having pairs of wheels at front and rear thereof, adapted to move along a road surface, a mold board carried at the side of the carriage and adapted to operate on the road shoulder, a fifth wheel mounted to clear the road, means for lowering said wheel so as to raise one of said pairs of carriage wheels, and separate means for raising the fifth wheel to provide greater clearance than is provided by said lowering means said fifth wheel being located off the center line of the carriage on the side supporting the mold board to facilitate balance of the entire machine when the mold board is extended.

2. In a road shoulder machine, a carriage, front and rear wheels on said carriage adapted to travel on the surface of a hard road, a mold board carried at the side of the carriage and adapted to operate on the road shoulder, means for engaging the edge of the hard road to hold the carriage in alignment, and means for adjusting the posi-

tion of said engaging means vertically and transversely.

3. In a road shoulder machine, a carriage, front and rear wheels on said carriage adapted to travel on the surface of a finished hard road, a mold-board for operation on the road shoulder, a flanged wheel adapted to engage the finished road edge to maintain the carriage in alignment, and means for adjusting the position of the flanged wheel vertically and transversely of the carriage.

4. In a road shoulder machine a wheeled carriage adapted to be drawn along a finished roadway, a mold board supported transversely of the carriage at the side thereof and adapted to operate on the road shoulder and means including a flanged wheel for facilitating holding the carriage in position at the edge of the road surface, said means including a screw threaded in the frame at the rear of the carriage wheels, a flange wheel axle, a pivot between the screw and axle whereby the axle may be moved to adjust the transverse position of the flanged wheel, and means for regulating the height of one end of the axle for raising and lowering the flanged wheel.

5. In a road shoulder machine a wheeled carriage adapted to be drawn along a finished roadway, a mold board supported transversely of the carriage at the side thereof and adapted to operate on the road shoulder and means including a flanged wheel for facilitating holding the carriage in position at the edge of the road surface, said means including a screw threaded in the frame at the rear of the carriage wheels, a flange wheel axle, a pivot between the screw and axle whereby the axle may be moved to adjust the transverse position of the flanged wheel, a second screw disposed vertically in the frame near the side thereof adjacent the flanged wheel, and means for connecting said screw with the axle to raise and lower the same.

6. In a road shoulder machine, a wheeled carriage adapted to travel along a finished roadway, a mold board, means for supporting the mold board at the side of the carriage, means near one end of the machine and near the side thereof carrying the mold board for receiving a screw, a screw adjustable vertically in said screw receiving means, a fifth wheel rotatably disposed at the bottom of said screw for engaging the road surface in making a short turn, and a hand wheel at the top of the screw for turning the same, said hand wheel also functioning to steer the fifth road wheel when it is in contact with the road.

7. In a road shoulder machine, a wheeled carriage adapted to travel along a finished roadway, a mold board, means for supporting the mold board at the side of the carriage, means near one end of the machine and near the side thereof carrying the mold

board for receiving a screw, a screw adjustable vertically in said screw receiving means, a fifth wheel rotatably disposed at the bottom of said screw for engaging the road surface in making a short turn, and a hand wheel at the top of the screw for turning the same, said hand wheel also functioning to steer the fifth road wheel when it is in contact with the road and means for supporting the screw securing means for raising the entire assembly to afford maximum road clearance.

In witness whereof, I hereunto subscribe my name this 7th day of June, 1930.

15
